UNITED STATES PATENT OFFICE.

FREDERICH W. BURGDORFER AND EDWARD F. RODDY, OF ST. LOUIS, MISSOURI.

MOLDING APPARATUS.

Application filed August 27, 1921. Serial No. 496,030.

To all whom it may concern:

Be it known that we, FREDERICH W. BURGDORFER and EDWARD F. RODDY, citizens of the United States of America, and residents of the city of St. Louis and State of Missouri, have invented certain new and useful Improvements in a Molding Apparatus, of which the following is a specification.

This invention relates to a molding apparatus, and has for its primary object the purpose of providing improvements in that class of apparatuses known as pattern stripping machines.

Another object of the invention is to provide an improved arrangement of pattern stripping parts in the molding apparatus.

A further object of the invention is to provide an improved molding apparatus for forming the mold or impression in the sand flask as the flask is passed thereunder.

A still further object of the invention is to provide an improved combination of a sand pressing element and a sand retaining frame, both of which are relevant towards operating on a sand flask in conjunction with a molding apparatus of this improved character.

Other and further objects will appear in the specification and be specifically pointed out in the appended claims, reference being had to the accompanying drawings exemplifying the invention and in which,

Figure 1 is a side elevation of a flask conveying device showing this improved molding apparatus in operable relation thereto.

Figure 2 is an enlarged vertical section taken through this improved molding apparatus.

Figure 3 is an enlarged vertical section similar to Fig. 2, but showing the patterns of the apparatus in the act of being molded or impressed within the packed body of the sand flask.

Figure 4 is a bottom plan view on a reduced scale of Fig. 2.

Figure 5 is a horizontal section taken on a reduced scale on the line V—V of Fig. 2.

Figure 6 is a horizontal section taken on a reduced scale on the line VI—VI of Fig. 2.

With reference to the accompanying drawings, this improved molding apparatus is comprised of a rectangular body portion 1, having vertical walls 2 and a bottom plate 3, said walls and bottom plate forming a closure 4, and extending upwardly from said bottom plate is a plurality of pins 5,

each supporting a coil spring 6, each of said springs at their lower end being seated against a boss 7.

Movably mounted within the closure 4 is a top plate 8, which is provided with a plurality of spring seats 9, each being for the reception of the upper end of a respective coil spring 6, and formed in each of said seats is a vertical bearing 10, each being for the reception of the upper end of a respective pin 5, and secured to the upper edges of the walls 2 by the studs 11 is an abutting frame 12, against which the edge 13 of the top plate 8 is adapted to abut by pressure 70 of the springs 6 thereagainst.

The top plate 8 serves as a pattern supporting plate, and from the disclosure of the drawings, circular patterns are provided, and in this instance designate piston ring 75 patterns 14, each pattern at its upper end being provided with a series of securing jaws 15 through which the bolts 16 are passed for securing them in suspended positions to the underside of the top plate 8, said patterns being of a length wherein when the top plate 8 is in elevated position as shown in Fig. 2, the lower edge 17 of each pattern will be flush with the lower face 18 of the bottom plate 3.

As disclosed in Fig. 4 of the drawings, four piston ring patterns 14 are shown, and so that each pattern can be depended through the bottom plate 3, circular openings 19 are provided, and located within each pattern is 90 an insert plate 20, the lower surface of each insert being held in flush alignment with the lower surface 18 of the bottom plate 3.

For supporting each of the insert plates 20 is a spider 21, each of said spiders being 95 comprised of a series of arms 22, which are formed integral with the upper surface of the bottom plate 3, the arms of each spider merging into a hub 23, each of the insert plates 20 being suspended from a respective 100 spider hub 23 by a screw 24.

In order for the piston patterns 14 to be suspended over the insert plates 20 as described, each pattern is provided with a series of vertical extending slots 25, there being a slot for each of the arms 22 of each respective spider 21, and when each pattern is secured to the underside of the top plate 8, the respective arms of each spider are engaged within respective slots of each 110 piston pattern.

The bottom plate 3 is provided with an

annular extending ledge 26, and vertically movable over said ledge is a sand retaining frame 27, having an inwardly extending portion 28 which is adapted to seat on said ledge.

Extending to each of the patterns 14 is a runner 29, each of said runners leading from a gate 30, said runners and gate either forming part of said patterns or may be suspended from the top plate 8 as are said patterns.

A molding apparatus of this improved character is to be operated above or adjacent a sand flask into which the pattern is to be pressed for forming the mold, but on account of the rapidity at which this improved apparatus can be operated, conveying means as shown in Fig. 1 are arranged for bringing up flasks which contain molding sand to the apparatus, said conveying means also being used for removing the flasks after the molding operation.

In connection with the above conveying means which is comprised of an endless belt 31 mounted over pairs of opposing sprockets 32, a standard 33 is mounted on each side of said belt, each of said standards supporting a bearing 34 at its upper end, said standards being secured together by the tying member 35, and supported by said bearings is a horizontally arranged shaft 36, and mounted on said shaft is a pair of cam wheels 37, each having a camway 38 formed sideways thereof, and mounted in each of said camways is a roller 39, each of said rollers being mounted on a respective end of a horizontally extending shaft 40, said shaft being mounted in bearings 41 which are upwardly extended from the top plate 8 of the pattern holding device which is mounted between the standards 33.

Extending from opposing walls 2 of the bottom portion 1 is a guiding member 42, each guiding member being vertically slideable on a respective standard 33. Secured to one end of the shaft 36 is a sprocket 43 from which is mounted an endless chain 44, said chain being co-operable with a sprocket 45 which is mounted on a shaft 46, and secured to said shaft is a spur gear 47 in mesh with an intermediate gear 48 which meshes with the power gear 49 of a motor 50.

Carried by the endless belts 31 is an apron 51, and arranged beneath the upper lap of said apron, intermediate of its ends and adjacent the standards 33, is a table 52.

In the operation of an apparatus of this improved character, molding sand which is contained in the hopper 53 is allowed to be entrained into a flask 54 which is mounted therebeneath on the apron 51, and as the flask is moved forwardly towards the molding or impressing apparatus, further designated as A, a horizontal levelling element 55 will level and form an upper sur-

face B to the sand within the flask 54. When the sand-filled flask 54 has been conveyed to a position directly beneath the molding apparatus A by power transmitted from the motor 50, the flask is arrested in exact 70 registering position by the actuation of intermittent arresting means such as disclosed in the U. S. patent to Fahnestock 1,027,116, and at this point the camways of the cam-wheels 37 will become 75 active on the rollers 39, thereby lowering the apparatus A downwardly and the sand retaining frame 27 will be lowered over the upper projecting surface B of the sand contained in the flask until the lower edge 56 80 becomes at rest on the upper surface 57 of the flask directly there beneath. During further operation of the cam-wheels 37 on the rollers 39, the body portion 1 is further lowered, and as the lower surface 18 of the 85 bottom plate 3 engages the raised surface B of the sand within the flask, said raised sand surface B will be pressed downwardly in the flask and when the sand resistance becomes too great for the pressure of the 90 springs 6 contained within the closure 4, said bottom plate 3 and insert plates 20 will be arrested or partially arrested by the sand pressure of the flask, and in which the top plate 8 will be forced downwardly towards the bottom plate 3, thereby forcing the patterns 14 and their runners 29 from the bottom plate 3 and the insert plates 20 to molding positions into the tightly pressed sand of the flask, thereby forming the impressions 100 of the patterns in the sand.

The cam-wheels 37 after forcing the patterns 14 into the pressed sand of the flask will withdraw said patterns from the molds which have been formed, and after said 105 patterns have been withdrawn within the bottom plate 3 the apparatus A is moved to an elevated position by said cam-wheels, and in which the retaining frame 27 will again be suspended from the ledge 26 of 110 the bottom plate 3.

After the apparatus A has been elevated, the flask bearing the impressions or molds of the patterns is moved to the position C from where it is removed from the apron 115 51, and as the flask was moved to the position C, a succeeding flask which has been filled with sand from the hopper 53 is moved to a position beneath the uplifted apparatus A.

From the aforementioned description of this improved molding apparatus, on account of the apparatus first pressing the sand into the flask and then molding the patterns and afterwards removing the patterns, it is obvious that a rapidly molding apparatus is afforded thereby.

What we claim is:

1. In a molding apparatus, the combination of an outer arranged stripping element,

an annular shaped imprinting element movable therefrom, and an inner arranged stripping element located concentrically of said imprinting element.

2. In a molding apparatus, the combination of a pair of stripping elements, and an annular shaped imprinting element movable therebetween.

3. In a molding apparatus, the combination of a stripping element, an imprinting element reciprocal therefrom, a second stripping element arranged interiorly of said imprinting element, and means for reciprocating said reciprocal element.

4. In a molding apparatus, the combination of a pressing element for engaging the sand in which an impression is to be formed, an impression forming element to be extended from said pressing element, and a second pressing element borne by said other pressing element arranged interiorly of said impression forming element.

5. In a molding apparatus, the combination of a pressing element for engaging the sand in which an impression is to be formed, an impression forming element to be extended from said pressing element, a second pressing element borne by said other pressing element arranged interiorly of said impression forming element, and there being means for extending said element.

6. In a molding apparatus, the combination of a yieldingly held sand pressing element, an impression forming element to be extended from said pressing element, a second pressing element borne by said first pressing element arranged interiorly of said impression forming element, and a movable frame depended from said first mentioned pressing element.

7. In a molding apparatus, the combination of a stripping plate, means whereby a sand flask can be arranged beneath said plate, an imprinting element movable from said plate into the sand of said flask, and an insert plate located interiorly of said element movable with said stripping plate.

8. In a molding apparatus, the combination of an outer stripping plate, means whereby a sand flask can be arranged beneath said plate, an imprinting element movable from said plate into the sand of said flask, an inner stripping plate arranged interiorly of said element, and means for operating said imprinting element towards and away from said flask.

9. In a molding apparatus, the combination of a pressing element, a sand flask to

be arranged beneath said element so that the sand contained therein can be pressed by said element, an impression forming element associated with said pressing element to be extended from said pressing element into the sand of said flask, and an insert plate arranged concentric to said impression forming element movable with said pressing element.

10. In a molding apparatus, the combination of a sand pressing element, an imprinting member reciprocal in said element, an insert plate co-operable with said member, means provided for supporting the sand flask in operating alinement with said element, means for reciprocating said member, and resilient means associated with said pressing element.

11. In a molding apparatus, the combination of a pressing element for engaging the sand in which an impression is to be made, an impression member co-operable with said element, and a movable frame into which said element is to reciprocate.

12. In a molding apparatus, the combination of a pressing element for engaging the sand in which an impression is to be formed, an impression forming element to be extended from said pressing element, and a reciprocable sand retaining frame into which said element is to reciprocate.

13. In a molding apparatus, the combination of a stripping plate, means whereby a sand flask can be arranged beneath said plate, an imprinting element movable from said plate into the sand of said flask, and a reciprocable sand retaining frame co-operable with said flask and into which said stripping plate is to reciprocate.

14. In a molding apparatus, the combination of a pressing element, a sand flask to be arranged beneath said element so that the sand contained therein can be pressed by said element, an impression forming element associated with said pressing element, and a reciprocable sand retaining frame arranged above said flask co-operable with said pressing element.

15. In a molding apparatus, the combination of a pressing element for engaging the sand in which an impression is to be formed, an impression forming element to be extended from said pressing element, and a reciprocable sand retaining frame into which said element is to reciprocate borne by said element.
